CLAIM

Oct. 9, 2001 (JP) 2001-029630

The ornamental design for a control panel of a portable electric computer, as shown and described.

(51) **LOC (7) Cl.** **14-02**

DESCRIPTION

(52) **U.S. Cl.** **D14/443**

FIG. 1 is a perspective view of the top, front and right side of the control panel for a portable electric computer showing our new design;

(58) **Field of Search** D14/441-446,

FIG. 2 is a front elevational view thereof;

D14/450, 399; D13/162, 184, 199; 312/223.2,

FIG. 3 is a rear elevational view thereof;

223.3; 361/690-696, 680-686, 724

FIG. 4 is a left side elevational view thereof;

(56) **References Cited**

FIG. 5 is a right side elevational view thereof;

U.S. PATENT DOCUMENTS

FIG. 6 is a top plan view thereof; and,

D221,951 S * 9/1971 Kindley D14/399

FIG. 7 is a bottom plan view thereof.

D275,105 S * 8/1984 Kuschewski et al. D14/443

The portions of the portable electric computer shown in

D290,707 S * 7/1987 Allen et al. D14/443

broken lines are not part of the claimed design.
